(57) **CLAIM**

The ornamental design for a combined salt and pepper dispenser, as shown and described.

DESCRIPTION

FIG. 1 is a front elevational view of a combined salt and pepper dispenser showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines are for illustrative purposes only and form no part of the claimed design.

1 Claim, 6 Drawing Sheets

FIG. 3

FIG. 5
